DESIGN FOR A COMBINED BOTTLE STOPPER AND LIQUID POURER

Adolph Berman, New York, N. Y., assignor to U. S.
Liquorgard Corp., New York, N. Y., a corporation of New York

Application June 4, 1937, Serial No. 69,672

Term of patent 3½ years

To all whom it may concern:

Be it known that I, Adolph Berman, a citizen of the United States, residing in New York city, county and State of New York, have invented a new, original, and ornamental Design for a Combined Bottle Stopper and Liquid Pourer, of which the following is a specification, reference being had to the accompanying drawing, forming part thereof.

Figure 1 is a top plan view of the combined bottle stopper and liquid pourer, showing my design; and

Figure 2 is a side view, slightly in perspective.
I claim:

The ornamental design for a combined bottle stopper and liquid pourer as shown.

ADOLPH BERMAN,
